CHAIN LINK

Henry St. Pierre, Worcester, Mass.

Application May 18, 1944, Serial No. 536,085

6 Claims. (Cl. 59—35)

1

This invention is directed to an improved method for making chain.

Objects of the invention include the provision of an improved joiner chain link which is made by forging a blank in dies, said blank being formed with a depression extending almost but not quite through the blank in a side edge thereof, and then cutting or breaking the blank in the region of the depression so that the blank may be separated either by twisting or bending to form an open joiner link which may be assembled with solid links. Then the link is welded, the depression forming a means for receiving welding metal poured or melted thereinto, and fusing the ends to finish the link. Thereafter the above described joiner link may be forged or restruck in dies in order to refine the weld, and to shape the link to the final form desired. Also the chain when welded may be heat treated to further improve the characteristics of the metal.

Further objects of the invention include the provision of a joiner link and method of making chain as above described in which the depression is formed in a stud link blank in a side run of the blank in the region of the stud; and the provision of a joiner link and method of making chain as above recited in which the depression is formed in a region of the joiner blank removed from the central part thereof, or from the stud area, so that each link may be assembled with but one link instead of two so that all links in the chain are the same rather than having solid links alternating with joiner links.

Other objects and advantages of the invention will appear hereinafter.

Reference is to be had to the accompanying drawings, in which

Fig. 1 is a plan view of a forged joiner link blank;

Fig. 2 is an edge view of the blank of Fig. 1;

Fig. 3 illustrates one method of opening the blank for reception of another link;

Fig. 4 illustrates a different method of opening the blank;

Fig. 5 is a plan view of a modified blank link;

Fig. 6 is an edge view of the link of Fig. 5;

Fig. 7 is an edge view illustrating one method of opening the blank; and

Fig. 8 is a view illustrating a different method of opening the blank.

In order to make the joiner link shown in Figs. 1 to 4 inclusive, I provide dies for forging out the blank of Fig. 1. This blank includes a solid side 10 and an opposite solid side 12, the link blank having ends 14 and 16 and in some

cases it will be desirable to have a stud 18 forming a pair of eyes 20 and 22. As thus described the blank is a solid link, but in addition to the above I provide a forged depression which may 5 assume any shape desired but is here shown as substantially circular, see 24 in Fig. 1. This depression may or may not extend completely through the link but it is preferred that it should terminate just short of one edge of the link as is 10 clearly illustrated at 26 in Fig. 2 thus providing a bottom 28, see Fig. 1. The sides of the depression 24 will be tapered as at 28 in Fig. 2 to provide for the draw necessary in forming. If it is 15 desired to have the depression 24 extend all the way through the blank this can be done in the forging operation or the bottom 26 can be punched out afterwards.

In any case the next step in the process of 20 making the chain consists of breaking the link or cutting it so as to separate the blank in the region of the depression to form a pair of ends 30, 32. It is not particularly desired to remove any material in this operation but this may be done if the link is ground off or sawed. The 25 breaking of the link results in the formation of the ends 30 and 32 as described and renders the depression 26 into two separate parts as at 34, 36.

As shown in Fig. 2 the end 14 may be bent to 30 separate end 32 from the end 30 and a similar link 38 is then inserted whereupon the end 14 is repositioned in its original location and the depressions 34 and 36 will then combine to substantially reproduce a single depression 24. When this has been done it is clear that a relatively 35 simple welding operation only is necessary to weld up the depression at a heat sufficient to fuse the two ends together not only at the depression but also in the bottom 26 and at the side edges of the depression, as indicated at 40, so 40 that the link becomes completely fused into a unitary joiner link.

In this form of the invention it is necessary that all links of the chain shall be the same inasmuch as the assembly takes place link by link, 45 that is link 38 is inserted over the end 14 in Fig. 3 and the link 38 in turn being the same as the joiner link disclosed will be opened up and a third similar link inserted therein.

In Fig. 4 I have illustrated a different method 50 of opening the link in which end 14 is twisted away from the end 30 instead of being bent as in Fig. 3. However, in any case, the joiner link itself and the method of making chain is substantially the same.

In Fig. 5 I disclose a modified form of the in-

vention in which there is a depression 42 and a bottom 44 therefor, as before, which are located however, centrally of the link at an end of the stud 18. In this case also the depression may be of any desired form but is shown for purposes of illustration as being circular and it is also enlarged over the depression shown in Fig. 1 because of the fact that there is an additional amount of material at this point in the link.

The method of making the chain is substantially the same as that above described except that in this case the welding step will also weld the stud at the same time, and that two solid links 46 may be assembled at once. The ends 48 formed by breaking the link may be twisted apart as shown in Fig. 7 or may be bent as shown in Fig. 8. However, it is to be particularly noted that depression 42 forms a part of the stud as is illustrated at 50.

In all forms of the invention the links may be coined and forged in dies, and allowed to cool, to make them conform to the shape desired as well as refining the weld and normalizing, and furthermore the chain may be heat treated to improve the characteristics of the metal.

Having thus described my invention and the advantages thereof, I do not wish to be limited to the details herein disclosed, otherwise than as set forth in the claims, but what I claim is:

1. Method of making chain comprising the steps of forming a blank in the shape of a link, forming a depression in a portion of the blank, splitting the blank at the depression, thus providing two ends, inserting at least one solid link, and welding the ends by filling the depression with molten metal.

2. Method as recited in claim 1 wherein the blank has a stud and the depression is located

in a side of the blank at an end of the stud, and including welding the stud to the said ends.

3. Method of making chain comprising the steps of forming a blank in the general form of a link, 5 making a depression in a side run thereof, breaking the blank at the depression to form ends each having a part of the depression therein, separating the ends, inserting a link, closing the ends, and depositing molten metal in the depression.

10 4. Method of claim 3 including the provision of a stud and breaking the link so as to separate the stud from the ends.

5 5. Method of making chain comprising the steps of forming a link blank, making a depression 15 therein in a manner to leave a bottom portion, splitting the link at the depression so as to leave a part of the bottom on each end formed by the splitting operation, inserting a link over one arm, and welding the arms together by deposition of welding metal in the depression.

20 6. Method of claim 5 including the provision of a stud and locating the depression at an end of the stud, the splitting operation separating the stud from the two ends, the splitting operation 25 also leaving a part of the bottom on the stud.

HENRY ST. PIERRE.
